UNITED STATES PATENT OFFICE.

NORMAN P. HARSHBERGER, OF CHICAGO, ILLINOIS.

COMPOSITION SHINGLE.

Application filed August 28, 1926. Serial No. 132,121.

This invention relates to composition shingles and has for its object providing a shingle the lap portion of which is locked down by other shingles, and one which can be conveniently cut from sheets of shingle material without waste. A further object of the invention is to provide such shingles which present a novel and pleasing appearance on the roof when assembled.

10 Of the accompanying drawings Fig. 1 is a plan view of the shingles which embody the features of my invention, as they appear when assembled on the roof; Fig. 2 is a plan view of a sheet of shingle material showing how the shingles are cut therefrom; Fig. 3 is a plan view of a single shingle; and Fig. 4 is a sectional view along the line 4—4 of Fig. 1.

The shingles 5 comprise a body portion 6, a shank portion 7, and a lap portion 8. Formed in the lap portion is a locking lug 9 and formed in the shank portions are aligning notches or fingers or guides 10. When the shingles are assembled on the roof they are laid in rows 11, 12 and 13, with the shank 7 of the left-hand shingle passing under the body portion 6 of the right-hand shingle of the same row; and with the guides 10 of the shank aligned with the lapping edge of the overlying shingle of the same row.

Each of the shingles has a lap portion 8 which is locked down by passing the lug 9 of the lap under the left hand end of the 35 underlying shingle in the adjacent row of shingles. The lefthand ends of the shingles overlap and hold down the right-hand ends of the shingles of the same row; and the underlying shingles of one row hold down the 40 lower edges of the shingles of the adjacent overlapping row, by means of the lug 9, which is fixed to the overlying shingles.

It will be seen that, as the shingles are cut from the sheet and then laid on the roof, one half of the shanks will have the fingers 45 and recesses 10 extending upwardly, and the other half will have them extending downwardly. But obviously this is immaterial as they are merely guides for aligning the shingles, in each row, with each other. The 50 shingles are positioned with reference to the shingles of the adjacent rows by the position of the lugs 9, and the ends 14. In this manner the shingles are quickly and accurately positioned and are also so interlocked as to 55 prevent warping, or bending up otherwise, of the lap portions thereof. Obviously also the shingles may be cut with the lugs 9 on the opposite side of the body portion so that the shank 7 may be extended towards the 60 left instead of towards the right.

I claim as my invention:

1. A rectangularly-shaped shingle, a rectangularly-shaped shank projecting from the central portion of one edge of the 65 shingle, and a lug fixed to an adjacent edge of the shingle, the outer edge of the lug being in line with the associated edge of the shingle.

2. A shingle according to claim 1 in which 70 the width of said shank is one-half the length of the side from which it projects.

3. A substantially square-shaped shingle, a substantially square-shaped shank projecting from the central portion of one edge of 75 said shingle, the area of the shank being substantially one-fourth of the area of the remainder of the shingle, and a slit projecting inwardly and angularly from the adjacent edge of the shingle.

In testimony whereof, I hereunto set my hand.

NORMAN P. HARSHBERGER.
